ATTORNEY

UNITED STATES PATENT OFFICE

WILLIAM F. GROENE, OF CINCINNATI, OHIO, ASSIGNOR TO THE R. K. LE BLOND
MACHINE TOOL COMPANY, OF CINCINNATI, OHIO, A CORPORATION OF OHIO

CRANKSHAFT LATHE

Application filed October 4, 1930. Serial No. 436,432.

My invention relates to machine for simultaneously turning the crank pins of a crankshaft for an internal combustion engine such as is used in automotive equipment and the like, particularly where two tools are simultaneously applied to each crank pin during the machine operation.

Among its novel features is one wherein the feed for the tools acts in a vertical line irrespective of the path of travel of the tool carrying arms. In other words, the arrangement is such that cams or cranks which impart movement to the tool holders relative to each other are driven in a straight line to and from each other, this line being in a vertical plane in the present arrangement.

Another novel feature is found in the arrangement of the drives for the master crankshafts, whereby it is possible to permit an increase of the distance between the shaft centers without in any way disturbing the synchronous timing of the shafts.

Another novel feature is found in the slides for preventing the chips and fine particles of metal from getting into the working parts of the machine.

In the drawings:—

Figure 1 is a front elevation of a lathe embodying my invention.

Figure 2 is a plan of the lathe.

Figure 3 is a section on line "A" of Figures 1, 2 and 4 of the lathe and shows the tool bars with their compensating drive and feeding arrangement.

Figure 4 is a partial plan of the lathe and shows the compensating drives of the master crank shafts.

Figure 5 is a fragmentary plan view, diagrammatic in character, of the drive for the feed to the tools.

Figure 6 is a fragmentary elevation, diagrammatic in character, of the drive for the feed to the tools.

Figure 7 is a plan view of a series of guard slides.

Looking now at the drawings, especially at Figures 2 and 3, the vertical frame members of the machine are shown at 1 and the horizontal ones at 2. A pair of bearing housings 3 are bolted to the front of the frame mem-

bers 1, and carry the spindles 4, these spindles having mounted on their inner ends toward the center of the lathe, air chucks 5, and at their outer ends have mounted double acting air cylinders 6 for operating the chucks.

The chucks 5 may be those of my Patent No. 1,723,347 of August 6, 1929, or any suitable air operated chuck and the air operating cylinders 6 may be any one of the many commercial types now on the market.

Mounted in bearings in the frame members 1 and 2, at their rear, is a master crankshaft 7 (Figure 3), this crankshaft being preferably of a larger diameter than the shaft to be turned by the lathe.

At the front of the lathe, mounted in ways 8 in the members 1 are sliding journal boxes 9, these journal boxes carrying the second and third master crankshafts 10 and 11. There are four journal boxes, two in each way 8, for the ends of the shafts 10 and 11. The arrangement of the shafts is such as to cause the working tools to correspond in their movement to the movement of the crank pins of a crankshaft mounted on its main axis and revolved by the lathe spindles.

On the top at the rear of the left hand frame member 1 is mounted a motor 12. Extending across the lathe and through the frame members is a drive shaft 13, having at its left hand end a gear train 14 meshing with the drive gear on the motor 12.

The gear train 14 is provided at 15 with a clutch member of any of the usual well known types.

On the right hand end of the shaft 13 is a gear 16 known as a "pick-off" gear, this gear meshing with a second pick-off gear 17, keyed on a stub shaft 18, mounted in bearings carried by the right hand frame member 1, this stub shaft also having mounted upon it a main drive pinion 19, this pinion meshing with gear 20 carried by the outer end of rear master crankshaft 7, thus driving the master crankshaft at a speed determined by the motor and the two pick-off gears 16 and 17. As the name implies, these pick-off gears may be of different ratios, and by changing them, the speed of the master shaft 7 and that

of spindles 4—4 may be varied to suit the work at hand.

The drive of the spindles will now be described (Figure 2).

10 A stud, mounted in the frame 1, carries a gear 21, this gear being in driving mesh with gear 20 of the rear master crankshaft 7, and in mesh with gear 22, mounted on a shaft carried in the frame 1,—this gear 22 in turn being in driving mesh with a pinion 24 on a shaft 23, this shaft 23 passing across the machine at the front and having on its left hand end, a pinion 25.

15 The two pinions 24 and 25, on the shaft 15 23, mesh with gears 26 and 27 mounted on the spindles 4—4 of the lathe, and thus furnish the drive for the spindles 4 and the chucks 5 and 6. Mounted upon and keyed to the rear master crankshaft 7, are gears 20 28 and 29, these gears being the beginning of a drive train of gearing for the two front master crankshafts 10 and 11.

The drive for the two front master crankshafts introduces a problem to be overcome, 25 since these two shafts furnish the feeding means for the tools that turn the work, in this case, an automotive crankshaft. At their outermost point of travel, the distance from the center of the rear master crankshaft to 30 the centers of the two front master crankshafts 10 and 11 is greater than it is when the two front master crankshafts are at their innermost point of travel. This occurs, by reason of the fact that the two front master 35 crankshafts in their approach and retreat to and from the work, do so in a vertical path in their sliding journals 9, and hence, as before stated, at their outermost point of travel the length of the angular center line is greater 40 than it is when the two shafts approach a horizontal center line.

It therefore follows, that under the above conditions, fixed gearing would be out of the question, and there must be some system 45 whereby the drive between the front and rear master crankshafts will compensate for this increase and decrease in the distance between the centers.

Such a system will now be described (Figures 2, 3 and 4).

Bearing bushings 30 are mounted in the frame 1 at the rear of the lathe and carry the end bearings of master shaft 7, these bearing bushings extending inward of the frame members 1 and have movably mounted on them arms 31 and 32, these arms forming projections from collars 32a that embrace the inner portions of the bushings.

At the front of the lathe and carried by the 50 movable journal boxes 9 of the front master crankshafts 10 and 11 are swingingly mounted arms 33 and 34, said arms being on collars 34a journaled on bosses formed on the boxes. Mounted in the outer ends of the arms 31, 32, 55 33 and 34 are long journal pins 35, these pins

35 acting as pivots for pairs of side bars 36 and 37, and also as the journals for gear wheels, as will be noted.

At the mid-length of side bars 36 and 37 and duplicated at each side of the machine, 70 is a journal pin 38, this journal pin having a shoe 39, on one of its ends, this shoe having taper sides 40 which engage a slide way 41 formed on the housing frame 1.

Mounted on one of the rear journal pins 75 35 at the left of the machine is a gear 42, this gear meshing with drive gear 29 on the master shaft 7; a second gear 43 is mounted on the journal pin 38 at the center of the side bars 36 and 37, this gear meshing with 80 the gear 42; a third gear 44 is mounted on the journal pin 35 at the end of the side bars 36, 37 furthest from the rear master shaft, this gear 44 meshing with gear 43 and with a gear 45 on the lower front master crankshaft 11.

It is to be seen that when the above described construction is completely assembled I have what may be called a gear cradle, carrying a train of gears and prevented from endwise movement, by reason of the central guiding ways 41, but being free to flex up and down on a center that is also free to move vertically. With this construction when the front master crankshafts are adjusted up or down there is a slight movement of the central pivot of the gear cradle up or down in a vertical direction while the ends under the influence of the arms 31 and 32 are forced to tip slightly in one direction or the other, dependent upon which way the master shafts are moving, the gears 44 and 42 walking slightly on the gears 28 and 45 on the rear and front master crankshafts, thus compensating for the increase or decrease of distance between the centers of the front and rear master crankshaft and at the same time maintaining the synchronism of the master shafts.

Looking at Figure 3, it should be noted that at the left end of the lathe the arm 32 points upward and the arm 33 downward, and that the gear 44 is above the gear 45 on the lower front master crankshaft 11. Just the reverse is found at the right hand end of the lathe. At this end the arm 34 is down and the arm 31 is up and the gear 46 is above the gear 28 on the rear master crankshaft, and the gear 47 is below gear 45 on the upper front master crankshaft 10. The gears 42 and 46 correspond otherwise than as to location, as do the gears 44 and 47. By this method, the drive from the rear master crankshaft 7 is relayed to the upper and lower master crankshafts 10 and 11 respectively.

The feed for the tools (the construction of which will be described later), is furnished by the movement of the two front master crankshafts 10 and 11 toward a central hori-

zontal line, and the means for accomplishing this will first be described.

Mounted in the frame member or tie bar 2 at the front of the lathe and extending downward within the ways 8 are feed screws 48 and 49. Since these two feed screws are alike and carry duplicate parts, the parts mounted on the two screws will be similarly numbered. Sliding in guide ways in the frame member 1, as has been noted, are the journal carrying boxes 9, each having a lateral guide extension 50 threaded for the passage of the feed screws 48, the extension on the upper box being threaded for a right hand thread and the extension on the lower box being threaded for a left hand thread. The feed screws 48 and 49 are likewise threaded right and left hand at their upper and lower sections respectively. It is manifest if the screws 48 and 49 be turned by any means, the journal boxes and whatever is carried by them, will move toward or away from each other, depending on the direction in which screws 48 and 49 are turned.

The means for turning the feed screws 48 and 49 will now be described.

Each feed screw 48 or 49 has fixed upon its upper end a bevel gear 51. Meshing with these bevel gears 51 are bevel pinions 52 mounted on a horizontal drive shaft 53, this drive shaft extending to the left and having loosely mounted on it, gears 54 and 55, these gears having clutch teeth on one side (Figures 5 and 6). A clutch member 56 is keyed, with sliding relationship, to the shaft 53, and is capable, when engaged to either of the gears 54, 55, of driving the shaft 53 from either of two sources of power.

For rapid traversing the feed screws, a reversing motor 56a is provided which is connected to gear 54 by gear train 57. The spindle drive shaft 23 which extends across the lathe, has at its left hand end, a gear 58, this gear meshing with a train of gears 59 which, in turn, mesh with gear 55 on the shaft 53.

Inspection of Figures 5 and 6 reveals that with the arrangement described the shaft 53 and the feed screws 48 and 49 may be driven at will from either of the two sources of power as the clutch member 56 is coupled to one or the other of gears 54 or 55, and thus feed the journal boxes 9 at slow speed or approach or withdraw them to the work by rapid movement, the slow feed derived from the spindle drive serving as cutting feed and the reversing motor drive as rapid traverse, as will be noted.

The tool carrying bars will now be described.

Looking at Figures 2 and 3, it will be seen that the tool bars 60 and 61 are in the form of flat arms having a depth much greater than their thickness, the width or thickness being

equal to the width of the pin of the crankshaft to be turned.

The upper and lower tool bars 60 and 61 are mounted at their rear ends on the eccentrics of the master crankshaft 7, an upper bar 60 and a lower bar 61 being paired to each eccentric, the end of each bar being split as at 62 to provide a detachable bearing on the eccentrics of the rear master crankshaft 7. The eccentrics on all master shafts match each other and are oriented alike, being held in orientation by their gear connections.

Near the front of each tool bar are pockets 63, these pockets providing space for a pair of half bearings 64, these bearings fitting the pockets top and bottom but having no bearing in the pockets at the front or rear. These bearings are thus free to adjust themselves forward or rearward, as occasion may require. These bearings are held in place by cap pieces 65 bolted to the edges of the tool bars, since any side movement is resisted by their fit between the throws of the eccentrics.

With the tool bars at their starting position, that is, with the master crankshafts 10 and 11 and the journal boxes 9, at their outward extremes of travel, the half bearing 64 at the front of the tool bars would be toward the front of the pockets 63. As the master shafts and the tool bars are fed toward the work, the tool bars describe an arc, pivoting on master crank 7, but the journal boxes 9 and the master cranks 10 and 11, travel in a vertical path as they are fed by the feed screws 48 and 49 so that when the tool bars 60 and 61 are at their innermost points of travel, the half bearing 64 will be at the rear of the pockets 63.

The construction above described makes possible the straight vertical feed of master crankshafts for a group of tool bars whose path of approach to the work is that of part of an arc.

The tools 66 are shown typically and form no part of this invention, since any of the many standard toolings may be used.

To protect the working parts of the machine from the chips and dirt incident to the turning of a crankshaft, a series of slides mounted in grooves in the front frame of the lathe are provided, which close the gaps in the front of the lathe frame above, between and below the tool bearing arms of each set.

Referring to Figure 1, it will be noted that the front of the frame is provided with a series of vertical bars 67 which space and act as side guides for the tool carrying members 60, 61.

Referring to Figure 7, it will be noted that I provide slides in groups of three arranged as best shown in Figure 3. The slides 68 are the outer ones of these series, the plates 71, the intermediate ones, and the slides 73, the inner ones of each series of three. The vertical grooves in the lateral walls of each mem-

- ber 67 serve to support and guide the plates of each series, there being naturally three sets of grooves in each instance. Referring first to the slide 73 which is the inner slide of each series, it is provided with a lower aperture 73a of a size to engage around the lower tool bar 61 and an upper slot 74 which is long enough to engage about the upper tool bar 60 and at the same time permit the upper bar 10 60 to travel away from the lower bar 61 to the limit of the separating movement between them. The opposite is true of the slide 68 which has a slot 68a at the upper portion thereof which fits around the tool bar 60 and 15 a long slot 70 which while it engages the lower tool bar laterally yet permits its movement away from the upper bar 60. The intermediate slide 71 is adjusted in position and held without sliding during the operation of 20 the machine. It has two slots 72 corresponding in length and function to the slots 70 and 74 of the inner and outer slides.
- For increasing the bearing area I prefer to provide pieces 69, one engaging the upper 25 end of the slot 68a of the outer slide for the upper tool bar and the other engaging the upper end of the slot 73a in the inner slide for the lower tool bar. These pieces 69 are grooved to receive the slot edges.
- 30 From the above it will be noted that the entire space behind the work is enclosed either by the tool bars themselves, one or the other of the slides or the vertically arranged frame members which form lateral bearings for the 35 tool bar.

Having thus described my invention, what I claim as new and desire to secure by Letters Patent, is:—

1. In a crank shaft lathe, a series of moving tool carrying frames, a support for the work in front of said frames, spacing bars between said frames, and enclosing the spaces between frames and means for maintaining closed the spaces not occupied by the frames, between said spacing bars.
2. In a crank shaft lathe, a series of moving tool carrying frames, a support for the work in front of said frames, spacing bars between said frames, and enclosing the spaces between frames and means for maintaining closed the spaces not occupied by the frames, between said spacing bars, comprising plates slidably held in the spacing bars, and engaging about the tool carrying frames.
3. In a crank shaft lathe, a series of moving tool carrying frames, a support for the work in front of said frames, spacing bars between said frames, and enclosing the spaces between frames and means for maintaining closed the spaces not occupied by the frames, between said spacing bars, said tool carrying frames arranged in pairs approaching the work from above and below.
4. In a crank shaft lathe, a series of moving tool carrying frames, a support for the work

in front of said frames, spacing bars between said frames, and enclosing the spaces between frames and means for maintaining closed the spaces not occupied by the frames, between said spacing bars, said tool carrying frames arranged in pairs approaching the work from above and below, the means for closing the spaces between spacing bars comprising plates slidably held in the spacing bars, there being a plurality for each pair of tool carrying frames, one engaging each frame, and having an opening engaging about the other frame sufficient to allow for its feeding movement with relation to the other frame.

5. In a crank shaft lathe, a series of moving tool carrying frames, a support for the work in front of said frames, spacing bars between said frames, and enclosing the spaces between frames and means for maintaining closed the spaces not occupied by the frames, between said spacing bars, said tool carrying frames arranged in pairs approaching the work from above and below, the means for closing the spaces between spacing bars comprising plates slidably held in the spacing bars, there being a plurality for each pair of tool carrying frames, one engaging each frame, and having an opening engaging about the other frame sufficient to allow for its feeding movement with relation to the other frame.

6. In a lathe of the character described, a rotary work holder and a plurality of rotary master shafts each having an eccentric surface, means synchronizing the rotation of said work holder and shafts, tool holders having each a bearing on the eccentric surfaces of two of said shafts and having its bearing on one of the eccentric surfaces slidable on the holder, and means to move two of the shafts for feeding each tool holder toward and away from the axis of the work holder.

7. In a lathe of the character described, a rotary work holder and a plurality of rotary master shafts each having an eccentric surface, means synchronizing the rotation of said work holder and shafts, tool holders each having a bearing on the eccentric surfaces of respective ones of said shafts and having its bearing on said eccentric surface slidable on the holder, and both tool holders having bearings on an eccentric surface of another one of said shafts, and means to move the first mentioned shafts for feeding each tool holder toward and away from the axis of the work holder.

8. In a lathe of the character described, a rotary work holder and a plurality of rotary master shafts each having an eccentric surface, means synchronizing the rotation of said work holder and shafts, tool holders each

having a bearing on the eccentric surfaces of two of said shafts and having its bearing on one of the eccentric surfaces slideable on the holder, an articulated mounting for said 5 synchronizing means, maintaining said means in operative relation to said shafts during the tool holder feeding movement of the two shafts, and means to move the two shafts for feeding each tool holder toward 10 and away from the axis of the work holder.

9. In a lathe of the character described, a rotary work holder and a plurality of rotary master shafts each having an eccentric surface, means synchronizing the rotation of 15 said work holder and shafts, tool holders each having a bearing on the eccentric surfaces of respective ones of said shafts and having its bearing on said eccentric surface slideable on the holder, an articulated mounting for 20 said synchronizing means, maintaining said means in operative relation to said shafts during the tool holder feeding movements of the two shafts, both tool holders having bearings 25 on an eccentric surface of another one of said shafts, and means to move the first mentioned shafts for feeding each tool holder toward and away from the axis of the work holder.

10. In a lathe of the character described, a rotary work holder and a plurality of rotary master shafts each having an eccentric surface, means synchronizing the rotation of 30 said work holder and shafts comprising gearing from the work holder to one of said shafts and sets of gearing from this one of the shafts 35 to others of said shafts, tool holders each having a bearing on the eccentric surfaces of two of said shafts and having its bearing on one of the eccentric surfaces slideable on the holder, and means to move two of the shafts for feeding 40 each tool holder toward and away from the axis of the work holder.

11. In a lathe of the character described, a rotary work holder and a plurality of rotary master shafts each having an eccentric surface, means synchronizing the rotation of 45 said work holder and shafts comprising gearing from the work holder to one of said shafts and sets of gearing from this one of the shafts to others of the shafts, tool holders 50 each having a bearing on the eccentric surfaces of respective ones of said shafts, and having its bearing on said eccentric surface slideable on the holder, and both tool holders having bearings on an eccentric surface of another one of said shafts, and means to move 55 two of the shafts for feeding each tool holder toward and away from the axis of the work holder.

12. In a lathe of the character described, 60 a rotary work holder and a plurality of rotary master shafts each having an eccentric surface, means synchronizing the rotation of said work holder and shafts comprising gearing from the work holder to one of said shafts and sets of gearing from this one of 65

the shafts to others of said shafts, and articulated mountings for the respective sets of gearing, maintaining the meshing of said sets of gearing during the tool holder feeding movement of two shafts, tool holders each 70 having a bearing on the eccentric surfaces of respective ones of said shafts, and having its bearing on said eccentric surface slideable on the holder, and both tool holders having bearings on an eccentric surface of another 75 one of said shafts, and means to move two of the shafts for feeding each tool holder toward and away from the axis of the crank holder.

13. In a lathe of the character described, a 80 rotary work holder and a plurality of rotary master shafts each having an eccentric surface, means synchronizing the rotation of said work holder and shafts comprising gearing from the work holder to one of said shafts 85 and sets of gearing from this one of the shafts to others of said shafts, each set of gearing comprising gears fixed on the respective master shafts and a train of gears from the gear of said one of the master shafts to the gear 90 of each other master shaft, tool holders, each having a bearing on the eccentric surfaces of respective ones of said other shafts, and having its bearing on said eccentric surface slideable on the holder, and both tool holders having 95 bearings on an eccentric surface of another one of said shafts, and means to move two of the shafts toward and from each other.

14. In a lathe of the character described, 100 a rotary work holder and a plurality of rotary master shafts each having an eccentric surface, means synchronizing the rotation of the work holder and shafts comprising arms swinging concentrically with the respective master shafts, link means connecting the arms, and guides for the middles of the links, and gearing from the work holder to one of the master shafts, gears fixed on the respective master shafts, gears rotating 105 concentrically with the respective connections of the link means to the arms, and a gear meshing with the latter mentioned gears and rotating at said middle of said link, tool 110 holders each having a bearing on the eccentric surfaces of respective ones of said shafts, and having its bearing on said eccentric surface slideable on said holder, and both tool holders having bearings on an eccentric surface of another one of said shafts, and means 115 to move two of the shafts for feeding each tool holder toward and away from the axis of the work holder.

15. In a lathe of the character described, a 120 rotary work holder, master shafts to the rear of and above and below the work holder, a third master shaft to the rear of the aforesaid master shafts, each master shaft having an eccentric surface, means for rotating said shafts in synchronism, tool holders fulcrumed 125 130

on the eccentric surface of the third master shaft and having slideable rotary bearings on the eccentric surfaces of the respective first mentioned master shafts and having extensions forward into proximity with the work holder, with means for holding tools to opposite sides of work held in said work holder.

16. In a lathe of the character described, a rotary work holder, master shafts to the rear of and above and below the work holder, a third master shaft to the rear of the aforesaid master shafts, each master shaft having an eccentric surface, means for rotating said shafts in synchronism with each other and with said work holder, tool holders fulcrumed on the third master shaft eccentric surface and having rotary slideable bearings on the eccentric surfaces of the respective first mentioned master shafts and having extensions forward into proximity with the work holder, with means for holding tools to opposite sides of work held in said work holder, and means having oppositely directed threads connected with the respective tool holders to feed said tools toward and away from the respective sides of the work.

17. In a lathe of the character described, three master crank shafts, bearings for the opposite end parts of said shafts, a work holder rotating in synchronism with the three crank shafts, two tool holders, both pivoted on the eccentric part of one crank shaft and having bearings on the eccentric parts of respective ones of the other two crank shafts, the bearings for the last mentioned crank shafts being slideable toward and away from each other to feed the tool holders toward and away from the work holder, two elements each having oppositely directed threads, each with its oppositely directed threads connected with respective bearings at one end of a crank shaft, and means for rotating said elements simultaneously.

45 WILLIAM F. GROENE.
